UNITED STATES PATENT OFFICE.

JOHN KOEHLER, OF NEW YORK, N. Y.

PRICE-CARD HOLDER.

SPECIFICATION forming part of Letters Patent No. 534,799, dated February 26, 1895.

Application filed June 22, 1894. Serial No. 515,896. (No model.)

To all whom it may concern:

Be it known that I, JOHN KOEHLER, of New York city, in the county and State of New York, have invented a new and Improved 5 Price-Card Holder, of which the following is a full, clear, and exact description.

My invention relates to a price card holder, or a holder adapted for the attachment of price cards to various articles, especially to 10 cigar boxes, to indicate, for example, the name of the cigars contained in the box and the price thereof; and the object of the invention is to provide a holder capable of receiving and retaining a card, which may be applied 15 in an expeditious manner, and capable likewise of being readily attached to the margin of a cigar box, clamping the surface to which it is applied; and furthermore to so construct the holder that the ticket holding section will 20 have a hinged connection with the clamping section, enabling the ticket-holding section to be drawn outward out of the way when cigars are to be removed from the box, or replaced 25 therein, thus obviating the possibility of damaging the cigars.

The invention consists in the novel construction and combination of the several parts, as will be hereinafter fully set forth, and pointed out in the claims.

Reference is to be had to the accompanying drawings, forming a part of this specification, in which similar figures and letters of reference indicate corresponding parts in all the views.

Figure 1 is a perspective view of a cigar box, illustrating the holder applied to one side thereof. Fig. 2 is a perspective view of the box, illustrating a holder attached to the end. Fig. 3 is a partial vertical section through the 40 box and through the holder, the holder being in the position shown in Fig. 1. Fig. 4 is a detail perspective view of the holder, illustrating the ticket-carrying section as carried to an essentially vertical position upon the 45 clamping section; and Fig. 5 is a section through the box and the holder, the holder being in the position shown in Fig. 2.

The holder may be said to consist of a clamping section A and a ticket-carrying section B. The clamping section is preferably made of one piece of metal of a spring character, being bent upon itself to form a body

10, having practically a flat upper surface and two legs 11 and 12 extending downward from the body. These legs are adapted to receive between them the surface of a box C to which the holder is to be applied. Preferably one of the legs 11 is made shorter than the other in order that the device may be more quickly applied, and it is curved downward and inward from one side edge of the body, while the longer leg 12 in being formed is carried beneath the body in direction of the shorter leg, and then downward.

A pintle 13, is formed in the top of the body 65 nearer one side than the other, and the said pintle is usually produced by cutting the metal of the body and bending it downward upon itself, as shown in Fig. 3; but the said pintle may be formed in any manner known 70 to the trade.

The ticket-carrying section B, is given any contour that fancy may dictate. In the drawings it is shown as rectangular, and consists of a plate 14, having its edges turned up and 75 over its outer face, forming marginal flaps or retaining flanges 15; and at or near the central portion of one edge of the said plate a knuckle 16, is formed, through which the pintle 13 of the clamping section extends, whereby the plate has a hinge connection with the clamping section and may rest upon the wider portion of the top of the said clamping section, in which position it will be inclined 80 downward, as shown in Fig. 3; and the said 85 ticket-carrying section may be carried to the vertical position, as shown in Fig. 4, or to an outwardly inclined position, as shown in Fig. 5. In either event the plate or ticket-carrying section will be entirely removed from possible engagement with the hand of the operator when he is taking cigars, for example, 90 from the box.

When the device is attached to the side of a box, as shown in Figs. 1 and 3, the members 95 of the clamp section are passed downward to an engagement with the inner and outer faces of the said side; and when the clamping section is in proper position upon the box the ticket-carrying section will face the opposite side, having a downward inclination. If the box containing the goods is so placed that one end faces the customer, the clamping section 100 will be applied to the outer end of the box, as

shown in Figs. 2 and 5, in which event it is desirable that the plate or ticket-carrying section should have an upward inclination. Therefore in this event spurs 17, are formed 5 upon the body portion of the clamping section, against which the plate will rest, as illustrated particularly in Figs. 4 and 5.

This device is exceedingly simple, durable and economic in its construction, and may be 10 expeditiously and conveniently applied; and prior to the operator placing his hand in the box to remove a portion of the contents, the plate or ticket-carrying section will be thrown upward either to a vertical position or to an 15 outwardly-inclined position away from the interior of the box, thus preventing the possibility of cigars, for example, being broken by contact with the plate, which often happens when cigars are removed from a box to which 20 an inwardly-extending price card holder is rigidly and immovably secured.

Having thus described my invention, I claim as new and desire to secure by Letters Patent—

1. A card holder consisting of a clamping section having a slotted head at its upper end

provided with an integral pintle, and a ticket carrying section having an integral knuckle entering the slot and turning on said pintle, substantially as described.

2. A price card holder, the same comprising a clamping section, consisting of a head having a pintle formed therein, and spring clamping legs projecting downward from the head, adapted to clamp an object placed between them, and a ticket-carrying section, consisting of a plate provided with a knuckle receiving the pintle of the clamping section, the knuckle being located at the back of one edge of the plate, the front or outer face of the plate being provided with marginal clamping flanges adapted to receive and retain a card, whereby the plate may rest upon the body of the clamping section in a substantially inclined position, or be carried upward and supported in a substantially vertical position, as and for the purpose specified.

JOHN KOEHLER.
